UNITED STATES PATENT OFFICE.

ROBERT ERNST FISCHER AND MAX WESCHER, OF ELBERFELD, GERMANY.

AUTOMATIC DISCONNECTING DEVICE FOR PAPER-TREATING MACHINES.

965,576.

Specification of Letters Patent. Patented July 26, 1910.

Application filed March 14, 1908. Serial No. 421,153.

To all whom it may concern:

Be it known that we, ROBERT ERNST FISCHER and MAX WESCHER, engineers, citizens of the German Empire, and residents 5 of 3-5 Sandstrasse, Elberfeld, Germany, have invented a new and useful Automatic Disconnecting Device for Paper-Treating Machines, of which the following is a specification.

10 This invention relates to a device for automatically throwing out of gear machines having rotatable rolls for treating paper as for example bag making machines, envelop machines and printing machines in 15 case of any accident arising.

This invention is illustrated in the accompanying drawing in which—

Figure 1 shows the device in the working position of the machine while Fig. 2 shows 20 the same in disengaged position. Fig. 3 is a detail view of a part of the same.

25 a , b , a^1 , b^1 , a^2 , b^2 , and a^3 , b^3 are several pairs of rolls provided with the instruments for working the paper. The guiding of the 30 paper from the one pair of rolls a , b to the next pair of rolls is effected by the guides e , f , e^1 , f^1 , e^2 , f^2 . The upper guides e , e^1 , e^2 , are stationary while the lower guides f , f^1 , f^2 are rotatable about an axis g , g^1 , g^2 and are 35 held by springs h , h^1 , h^2 in the position shown in Fig. 1.

If any accident should happen on the 40 passage of the paper from one pair of these rolls the paper is piled or heaped up behind 45 these rolls as shown on the left hand side of Fig. 2 and this piled up paper presses down the lower guides into the position shown by f in Fig. 2.

On the axle i of the roll b^1 is fixed a 45 cam disk j on which runs a roller m secured to the lever l mounted at k so that this lever l during the operation of the machine swings up and down about the pivot k . The lever l moves in a slot in the rod p 50 which is pivoted at n to the double armed lever o which rod is pressed by means of a spring q against a stop pin r of a rod c connecting the levers s , s^1 and s^2 secured to the 55 guides f , f^1 and f^2 . If now by some accident as above indicated one of the guides is brought into the position shown by f in Fig. 2 when the pin r moves backward and the rod p follows the action of the spring q , a lug t on the lever l enters the slot in the 60 rod p . This slot which is represented by the dotted lines u and v is of such length

that on the lifting of the lever l by a cam on the cam disk j the rod p is carried with it, whereby the lever o swings about the pivot r and a pin h attached to the same is thereby withdrawn from a notch in the disconnecting rod y . This rod which is held in position by the pin h is now moved under the action of a spring y^1 , a weight or the like, in such manner that the machine is 65 thrown out of gear by the belt-guide y^2 throwing the driving from the fixed to the loose pulley. When the piled up paper is removed the several lower guides return to the position shown in Fig. 1 under the action of their respective springs, the rod p being pressed back by the pin r . If the machine is again brought into gear, the disconnecting rod y being brought back into its former position, the pin h again enters 70 the notch in the rod y under the action of the spring z , whereby the rod p is again drawn downward and the device again brought into operative position.

Thus in case of accident this device effects 80 the disengagement of the machine which cannot again be brought into gear until the paper causing the accident is withdrawn from the machine.

What we claim as our invention and desire 85 to secure by United States Letters Patent is:—

1. In a machine of the character described, the combination with the rotatable rolls, of a 90 pair of guides for guiding the paper between the rolls, one of said guides being yieldingly mounted, mechanism for throwing the machine out of gear, means controlling said mechanism, a swinging member actuated by 95 one of the rolls and adapted to operate the controlling means, a stop normally holding said controlling means out of the path of movement of the swinging member, and means controlled by the yielding guide for 100 causing said stop to be removed when the paper accumulates on the yielding guide whereby to effect the actuation of the machine stopping mechanism.

2. In a machine of the character described, the combination with a pair of rotatable 105 rolls, of a pair of guides for directing the paper between the rolls, said guides comprising a fixed and a movable member, said movable member being pivotally mounted and adapted to be depressed by the accumulation and pressure of the paper between 110 said guides, a lever adapted to have swing-

ing movement through the rotation of one of said rolls, and a means adapted to be engaged by said swinging lever and effect to throw the machine out of gear when the 5 paper accumulates between said guides.

3. In a machine of the character described, the combination with a plurality of pairs of rolls, of a pair of guides for supporting and directing the paper between adjacent pairs 10 of said rolls, one of each pair of guides being yieldingly mounted and adapted to be depressed by the accumulation and pressure of the paper between said guides, levers depending from said movable guides and having 15 a common connection, a pivotally mounted lever adapted to have swinging movement

through the rotation of one of said rolls, and a means adapted to be engaged by said swinging lever to effect the throwing of the machine out of gear when the paper accumulates between any one of the pairs of guides, 20 said throwing out means being held inactive during the running of the machine through the common connecting means of said levers.

In testimony whereof we have signed our 25 names to this specification in the presence of two subscribing witnesses.

ROBERT ERNST FISCHER.
MAX WESCHER.
